UNITED STATES PATENT OFFICE.

JOHN ASHWORTH, OF SOMERVILLE, MASSACHUSETTS.

COVERED ELASTIC ENDLESS BAND.

SPECIFICATION forming part of Letters Patent No. 423,713, dated March 18, 1890.

Application filed November 19, 1887. Serial No. 255,661. (No model.)

To all whom it may concern:

Be it known that I, JOHN ASHWORTH, of Somerville, in the county of Middlesex and State of Massachusetts, have invented a new 5 and useful Improvement in Covered Elastic Endless Bands, of which the following, taken in connection with the accompanying drawings, is a specification.

The object of this invention is to produce 10 an improved extensibly-elastic covered endless band, designed especially for use as an armlet or a stocking-supporter, and useful generally where an ornamental and protected endless band is required.

15 The peculiarity which distinguishes my improved band from all others is that two or more endless elastic cores, each having an endless and seamless sleeve or envelope wound or braided upon it, are united laterally by a 20 thread, which passes alternately entirely around each of such covered cores and is looped or formed into a stitch between such adjacent cores, the outer edges of the band thus begun being ornamented by a looped or 25 knitted border, the threads of each border surrounding one of the covered cores and forming an ornamental looped edge thereon, while the threads forming such edges or borders are bound or held in place by an additional binding-thread, so that they cannot 30 twist out of position.

I do not herein claim, broadly, a covered elastic endless band, as I have obtained other 35 patents thereon, one—No. 409,001, dated August 13, 1889, on my application filed May 11, 1881, and another, No. 345,660, dated July 20, 1886, on my application filed October 3, 1885.

In the drawings, Figures 1 to 4 represent 40 sections of the band expanded to bring before the eye the different threads and stitches of the covering, as hereinafter explained, although the band is formed symmetrically by the several stitches taken simultaneously, and not by completing one part in advance 45 of the other. Fig. 5 shows the band complete, one having two cores being selected for illustration.

A represents the elastic core, an endless band of india-rubber, and B is the primary 50 covering thereof, formed seamless and endless by winding or braiding threads thereon, so as to conceal and protect the core and

leave it extensibly elastic. Two of these covered cores are shown to avoid unnecessary complication in the figures.

55

C is the thread or cord which unites laterally the covered strands B B, said thread passing entirely around each of said strands alternately and between the two at each such passage, forming between them a stitch or 60 loop after every passage around either one. This serves to hold the covered strands very slightly apart, and secures a flat character to the band, instead of it being nearly or practically round by winding around both 65 strands at once. On each edge of the band I form a looped border, which is made of a thread or cord D or E, passed simultaneously with the thread C around one of the covered strands B and alternately around a part of 70 the machine by which said thread D or E is held temporarily, as by another band, so that a succession of loop-stitches is formed by each thread D or E along one edge of the band. While one thread D is forming the border 75 along one edge the other thread E at the same time is similarly forming a like border on the other edge of the band by alternately passing around the other strand B and around a part of the machine, forming a succession of loops, 80 a knot or stitch being in each case formed after such thread D or E has passed around the strand B and before it forms a loop of the border, and also after forming such a loop and before passing again around the strand B. In 85 addition to this border, the band has a binding-thread F, Figs. 4 and 5, introduced for the purpose of holding the loops of the two distinct border-threads D E from turning on the strands B B. This thread F is interwoven 90 with the threads C, D, and E in such a way that it engages with each loop of the border, as seen in the heavy black lines of Fig. 4, crossing at the back of the band, as in Fig. 5, alternately from one border to the other. It 95 will be understood that the covered cores A B are stretched in a suitable extended position in the machine, and that the several subsequent operations above described go on simultaneously and form the band complete 100 with both its borders and the binding-thread applied at the same time.

I claim as my invention—

As a new article of manufacture, an end-

less extensibly-elastic band having two or more separately-covered elastic cores united laterally by threads passing alternately around each covered core and between those 5 adjacent to each other, said band having on its edges borders formed by looped threads D E, and provided with a binding-thread engaging the loops of both borders, substantially as set forth.

In testimony whereof I have signed my name to this specification, in the presence of two subscribing witnesses, on this 16th day of November, A. D. 1887.

JOHN ASHWORTH.

Witnesses:

A. H. SPENCER,
B. MARVIN FERNALD.
